OXYGEN GENERATOR WITH INTEGRATED
INITIATING DEVICE

Glenn A. Millikan, Nashville, Tenn., and Victor A. Legallais, Philadelphia, Pa., assignors to the United States of America as represented by the Secretary of War

Application June 12, 1947; Serial No. 754,218

10 Claims. (Cl. 128—203)

The invention described herein may be manufactured and used by or for the government for governmental purposes without payment to us of any royalty thereon.

This invention relates to an oxygen generator and breathing device for use by aviators at high altitudes.

It is known that aviators at high altitudes may be subjected to emergencies such as the rupturing of a pressurized cabin, so that they must have oxygen to breathe within a few seconds after their normal air supply is taken away from them. Under such conditions, it is necessary for survival to have an oxygen generator which can start suddenly and reliably and which requires a minimum of manual operation to initiate.

One object of this invention is to provide an oxygen generator of the quick starting type which will not void oxygen unless it is being breathed.

Another object is to provide an integrated initiating device for the generator which will simultaneously open the canister seal, the bag seal, and initiate the burning of the chlorate candle, which generates most of the oxygen during the first three minutes of operation.

Another object is to provide an oxygen unit which will furnish a reserve of usable oxygen after the generating chemicals are exhausted.

Another object is to provide an oxygen generator which is unusually compact and may be worn before use, without the breather bag being inconveniently unfolded.

In the drawings:

Fig. 1 is an oblique view of an aviator wearing our device;

Fig. 2 is a vertical section of our device showing the generator, the closures thereof and the breather bag, therefor;

Fig. 3 is a perspective view of the top of the generator while it is still unactivated;

Fig. 4 is a perspective view of the top of the generator after it has been opened, i.e., activated;

Fig. 5 is a perspective view of the bottom of the generator while it is in process of being activated;

Fig. 6 is a vertical section of an exhalation valve for the mask. The valve is shown open;

Fig. 7 is an edge view of the same valve closed; and

Fig. 8 is a plan view of the same valve closed.

In Fig. 1, the principal parts of the device are shown in use, together with a mask. 10 is an oxygen generator of generally cylindrical shape,

11 is a breathing bag attached thereto, 12 is a flexible breathing tube attached to a mask or facepiece, 13.

In Fig. 2, the generator 10 appears on a greatly enlarged scale, compared to Fig. 1, and approximates actual size. 11 is a breathing bag, which is extended. The flexible rubber tube 12 is shown broken away. On the left side of generator 10 there is a clip 14 for attaching the generator to the aviator's clothing or harness. On the right side (see also Fig. 3) is a ball 15 of a size which will fit easily into the palm of the hand, and a wire cable 16 for initiating the generator. As will be seen from Fig. 3, the cable 16 is, before initiation, attached to a starting lever 17 which locks an exit pipe 18 to which the rubber tube 12 is attached when the generator is in use. The starting lever 17 has a yoke shape and is detachably hinged to two lugs 19 and 19a which are parts of a shelf 20 which lies under the top surface of the generator 10. A stopper 21 is attached to the under side of starting lever 17 by a bolt 22 and a nut 23. When the lever 17 is down, the stopper closes the exit pipe 18.

An inner metal canister 25, together with its contents, comprises an oxidizing cartridge, and contains active material. The entire generator unit is designed as a cheap, expendable device which is to be discarded when exhausted. An alternative, but heavier, design could utilize a replaceable cartridge. A wall portion 26 of the canister 25 is preferably covered on the outside with glass cloth 24 or other thermal insulation which may extend around and protect the rubber breathing bag 11. The insulation 24 serves to keep the chemical reaction in the generator from dying out. The bag 11 and a protective cover 24a therefore are intended to be folded and retained adjacent to the bottom of the generator 10. A pair of spring-opened doors 27 and 27a (Fig. 5) serve the purpose of ejecting the folded bag from its resting place and largely opening it. Inflation is primarily caused by the rapid production of gas by a chlorate candle primer or igniter which is later described.

Before the generator is used, there is a thin brass seal 60 (see Fig. 2) which is then intact but later, upon activation of the generator, broken by a small guillotine 61 which has a spade-shaped knife 62. In Fig. 2, the knife 62 has ruptured the seal 60. Both the guillotine 61 and the double doors 27 and 27a are actuatable by a mouse-trap type of spring 63 which is wound over a mandrel 64. The inner ends of spring 63 are

attached to the doors 27 and 27a while a loop 25 is attached to the guillotine.

Referring again to Figs. 3 and 4, 28 and 28a are reserve starting levers for additional chlorate candles. The candles are activated by a pull on a trigger wire 29 on the end of which is a small ball 30. The reserve starting levers 28 and 28a bear slots 31 which retain the balls 30 sufficiently long during a pull on the cords 29 to activate the candles. Lugs 32 serve as fulcrums for the levers 28 and 28a. Extending from starting lever 17 and over the reserve levers 28 and 28a, there is a yoke 28b which fits under lugs 19 and 19a. It is provided with a slot 31 which holds the starting ball 30 of the middle chlorate candle. A tab 33 which is part of a guard 34 for reserve lever lifting rings 35 and 35a extends upward through a slot in the bag release member 38. The guard 34 is in turn retained over the rings 35 and 35a by the pressure of a strap 36 which extends from a slot 37 in the rear end of a bag release member 38 which fits under the starting lever 17. Yoke 28b will clear lugs 19 and 19a without a rearward motion because of the fact that there is enough give in the parts 38, 19, 19a, and 28b to allow the force acting on the lever 17 to free yoke 28b from the lugs 19 and 19a. The strap 36, as will be seen from Fig. 2, fits about the folded bag 11 and its cover 26. Release of the bag release member 38 allows the bag 11 to fall while strap 36 retains the bag release member 38.

In Fig. 4, is shown a check valve 39 which fits inside the exit pipe 18. After the stopper 21 is lifted, the valve 39 remains closed to prevent egress of oxygen until a suitable concentration of this gas has built up.

In using this invention, it is necessary that the mask 13 contain a valve 41 of the kind shown in Figs. 6, 7 and 8. The purpose of this valve is to selectively shut off exhalation to the atmosphere from the mask so that the wearer's breath must return to the bag 11 via the generator 10. Its location is in the front of the mask in the exhalation port. The rubber side of the valve 41 faces the interior of the mask. A loading of the mask interior to a pressure of about 5 cm. of water is desired.

42 is a cylindrical rubber body of valve 41. Its section is shown in Fig. 6. 43 and 43a are two individuals of a plurality of openings extending entirely through the body 42. 44 is a circumferential channel on the body 42 by which the valve may be held in the mask 13. 45 is a screw which extends through the body 42 and retains between an inner nut 46 and an outer nut 47, a snap diaphragm 48 which loosely encloses by means of ears 49 a second snap diaphragm 50 and an actuator 51 therefor. Actuator 51 is centrally perforated at 52. Behind the diaphragms 48 and 50 is a rubber cap 53 which has very little thickness, thereby making it possible to overlie the beveled edges 54 of the valve body 42 and close the openings 43 and 43a.

When the valve is closed, as shown in Fig. 7, the diaphragm 50 is straight and diaphragm 48 is bent backward over diaphragm 53. By grasping the edge of diaphragm 48 and pulling it away from the body 42, the diaphragm 48 will snap to the position shown in Fig. 6, allowing diaphragm 53 to lift from openings 43 and 43a thereby sealing them.

Interiorly the generator 10 is divided by a wire gauze partition 70 into a guillotine operating space 71; by two other such partitions 72 and 73,

upper and lower respectively, into an oxygen generating space and by another partition 75. Woven glass fiber is incorporated in each partition to keep the KCl and other solids which are generated by candle combustion within the candle space by filter action. Woven glass fiber is also employed to hold the KO₂ in place on the walls. In order to keep the temperature below 150° C., above which the filtration of chlorides through the woven glass fiber is hindered, some heat-absorbing substance such as hydrous copper sulfate CuSO₄.5H₂O or potassium-permanganate impregnated active carbon may be placed between the candle and the filtering partitions, as for example, at 87.

In the valve 39 there is a stem 76 which is vertically slidable in a tube 80 which is held erect in holes in the gauze partitions 72 and 75 by solder. Below the diaphragm 40 of valve 39 there is a weak coil spring 78 which is compressible by any pressure in the tube 12 which is greater than 5 cm. of water. Therefore it is compressible by breathing pressure. The valve 39 is maintained in a fully open position while the device is being worn. The mask connector of the breathing tube 12 engages with the cross bar of the valve 39. Inhaled and exhaled air passes freely through this open valve. When the unit is disconnected and laid aside for a time the valve is closed, thus conserving the oxygen in the connector and bag.

The generating space between gauze diaphragms 72 and 73 is lined as to its vertical walls with a charge of potassium peroxide, KO₂ or K₂O₄ sometimes known by its commercial name "KOX." This substance will absorb CO₂ and water and will liberate 1½ mols of oxygen for each mol of carbon dioxide or water absorbed. Since this reaction demands that CO₂ or water be furnished as starting material, it cannot furnish ready oxygen as soon as the mask is put on. Therefore three chlorate candles, of which two, 81 and 82 respectively, are shown in Fig. 2, are provided. Candles having the following composition are satisfactory as self-propagating oxygen generators:

Per cent by weight	
Sodium chlorate	81
Iron powder	10
50 Barium peroxide	3
Powdered glass fiber	6

On candle 81 there is shown a red phosphorous-antimony trisulfide-potassium chlorate igniter 55 similar in principle to the well known Bickford pull-fuse or box-striking safety match. It comprises a case 83 to which is attached a second case 84. The latter contains a spring 85 of sheet material which is adapted to rotate a rough chemical-coated friction plate 85a on a composition 85b; friction between the plate 85a and composition 85b produces ignition. The lower end of pull wire 29 is adapted to trigger the spring 85. A vertical tube 86 is provided to guide the wire 29.

65 In operation, the ball handle 15 is pulled thereby lifting lever 17 through cable 16. The pull may be a single motion of one hand. Stopper 21 is lifted out of exit pipe 18. The same pull of lever 17 is exerted on wire 29 to trigger the coil spring 85 to rotate the friction plate 85a on the initiating chemical 85b. Friction between the chemicals initiates combustion of the chlorate candle 81, thus generating oxygen. This effect is due to the heating of that excess chlorate in the 75 candle which does not react with the combustible

candle constituents. The wearer now inhales oxygen.

Meanwhile the pull on lever 17 has released strap 36 which drops and releases bag 11. The doors 27 and 27a now relieved of the pressure of the bag, fly open under the urging of spring 63. Guillotine 61 simultaneously cuts the seal 60. The chlorate candle immediately liberates oxygen at a rate which completely fills the canister, and expands the bag in a few seconds. Excess oxygen is vented if the mask has already been connected, through the loaded expiratory valve in the mask.

The three oxygen candles act only as one initial primer and two final reserves of oxygen. They liberate enough oxygen to supply the flier for only five to ten minutes, but they do it quickly and positively. The "KOX," which supplies oxygen in accordance with need according to the CO_2 and water vapor reaching it, provides an adequate regular supply of oxygen to the wearer for the 1-2 hour duration of the unit. The "KOX" is supplemented by the chlorate candles because (a) "KOX" starts sluggishly, especially in the cold, (b) a large excess of oxygen is needed at the start of operation to flush out the system with pure oxygen, and (c) a small reserve of oxygen should be instantly available after a collapse signals the wearer that the "KOX" has become exhausted.

Numerous changes and substitutions may be made without departing from the spirit of the invention as defined by the appended claims.

The invention claimed is:

1. In an oxygen generator, the combination which comprises a canister, oxygen generating means within said canister, an exit pipe on the top of said canister, a seal for the top of said exit pipe, initiating means for said oxygen-generating means, a lever attached to the top of said canister adapted to unseal the exit pipe, said initiating means being attached to and actuatable by said lever, said generator having in addition a breathing bag foldedly attached to the bottom of said canister when the generator is not in use, bag-retaining means attached to the lever and extending around the folded bag, said bag-retaining means being releasable by the operation of said lever, a seal between the bottom of the canister and the bottom of the bag and means attached to the bottom of the canister for rupturing the seal upon release of the bag.

2. The combination recited in claim 1 in which the seal rupturing means comprises a mouse-trap type of spring, a guillotine carried on a loop thereof, and two downwardly opening doors movable by the spring ends to open the bag.

3. In an oxygen generator, a canister, thermal insulation around said canister, a breathing bag foldedly attached to the bottom of said canister when the generator is not in use, said insulation extending around said breathing bag to protect the latter, an exit tube for oxygen extending from the top of the canister, unsealing means comprising a lever and a stopper attached thereto, said stopper being normally in said exit pipe but removable therefrom by movement of said lever, bag-retaining means releasable by the same motion of said lever, a plurality of chlorate candles within said generator, initiating means for each candle, said initiating means being actuatable from the top of the canister, the initiating means for one candle being actuatable by the movement of the lever to unseal the exit pipe and release the bag.

4. The combination set forth in claim 3 plus

means carried on the bottom of the canister for simultaneously spreading the folded bag and opening communication for gas between the interior of the canister and the interior of the bag.

5. In combination in an oxygen supply unit, a generator, a breathing bag folded under said generator, an exit pipe for oxygen from the top of said generator, a seal for said exit pipe, multiple oxygen generating charges within said generator, a seal between said generator and said bag below said generating charges, means for igniting each generating charge from the top of the generator, lever means for unsealing said exit pipe, release means controlled by said lever means for dropping said bag and rupturing said lower seal, one igniting means for a generating charge being actuatable by the movement of said lever whereby the generator may be put into operation by one movement of one hand.

6. The combination recited in claim 5 and in addition, a filling of potassium peroxide on the interior of the generator.

7. A rebreather oxygen supply unit comprising a generator, thermal insulation about said generator for promoting the chemical reactions taking place therein, a filling of a water and carbon-dioxide absorbing substance, a plurality of unit charges of a chemical mixture which generates oxygen upon initiation of combustion therein, separate means for initiating combustion in each unit charge, a breathing bag foldedly attached to the bottom of the generator when the latter is not in use, spring actuated means for opening the bag and establishing gaseous communication between its interior and the interior of the generator, lever means hingedly fulcrumed on said generator for opening a top exit therefrom, a strap releasable by the operation of said lever means for releasing the bag and freeing the spring actuated bag opening means, a wire connected to said lever means and to the combustion initiating means whereby actuation of the lever means will pull the wire and so initiate combustion of one oxygen generating charge.

8. In an oxygen supply unit, a generator, an oxygen generating system in said generator comprising a plurality of chlorate candles, separate ignition means for each candle and a charge of a carbon dioxide and water-absorbing, oxygen-generating chemical arranged to have an extensive surface, a rebreather bag on said generator, an exit pipe from the top of said generator to a pressure mask, a valve in said exhaust pipe for connection to prevent loss of oxygen when the device is open but not in use, and for the accumulation of a reserve supply available for breathing from said bag after all of the chemicals in the generator have become exhausted.

9. The combination recited in claim 8 plus wire gauze partitions at the top and bottom of that space in the generator which contains the oxygen generating chemicals, said partitions comprising glass fibers being adapted to filter solids from the gas generated by said chemicals, said partitions at least in part supporting the valve for preventing loss of oxygen when the device is open but not in use.

10. In combination in an expendable oxygen-generating system, a generator, oxygen generating means in said generator comprising a filling of potassium peroxide arranged to have an extensive surface and capable of furnishing most of the oxygen, a plurality of chlorate candles mounted vertically within said generator, the first candle being able to furnish oxygen suffi-

cient for breathing during approximately the first three minutes of operation, filter means at the top and bottom of said generator, separate means for initiating combustion in each chlorate candle, a breathing bag foldedly attached to the bottom of the generator when the latter is not in use, spring-actuated means for opening the bag and establishing gaseous communication between its interior and the interior of the generator, lever means hingedly fulcrumed on said generator for opening a top exit therefrom through the top filter, a strap releasable by the operation of said lever means for releasing the bag and freeing the spring-actuated bag-opening means, a wire connected to said lever means and to the combustion initiating means whereby the actuation of the lever means will pull the wire and so initiate the combustion of one chlorate candle.
